FENCE POST CLIP

Donald C. Gardner, Salt Lake City, Utah, assignor
to The Colorado Fuel & Iron Corporation, a corporation of Colorado

Application August 22, 1939, Serial No. 291,311

6 Claims. (Cl. 256—57)

This invention relates to fence structures of the type including posts and clips for securing fence wires to the posts. More particularly, the invention is concerned with a novel fence including clips which may be applied quickly and easily to provide permanent fastenings for the wires and which are superior to prior fence clips by reason of their inclusion of a novel feature of construction whereby the clips may be drawn tightly around the posts after being attached thereto and thus hold the wires more securely.

Wire fences as commonly made heretofore comprise strands of wire connected to the posts by clips each of which is secured at one end to a post and extends across the front face of the post where it is passed over one of the fence wires. The clip is then drawn around to the back of the post and secured thereto in any suitable manner, as by means of a hook on the clip which hooks over a part of the post. Such fences have not been entirely satisfactory heretofore because the clips cannot be tightened after they are secured to the posts, and accordingly the fence wires are sometimes held loosely by the clips. This looseness of the wires allows them to rub against the posts and the clips with the result that the usual protective coating of zinc, or the like, is worn off the wires and the clips.

The present invention, therefore, is directed to the provision of a novel fence which includes a clip so constructed that it may be easily tightened around the post to the desired extent after it is secured to the post.

The new fence comprises posts each having a flange extending lengthwise thereof, and clips made of heavy wire for securing the fence wires to the posts. Each clip is secured at one end to the post and extends along the front face thereof and over one of the fence wires. The clip is then bent around one side of the post and hooked over the flange, the hook for this purpose being preferably formed on the clip before it is supplied to the user. The hook and the clip are so formed that when the clip is thus secured to the post, the end of the hook is adjacent one side of the flange and there is a considerable space between the edge of the flange and the body of the hook. Accordingly, when the hook is hammered toward the side of the flange adjacent the end of the hook, it acts as a lever fulcruming on that side of the flange and about the end of the hook, thereby drawing the clip tightly around the post. With this construction, the clip can be applied quickly and easily since it may be secured to the post loosely and then tightened to

the desired extent by bending the hook around the flange. It will be apparent that the parts of the fence may be made with wide tolerances because any looseness of the clip is taken up by bending the hook.

For a better understanding of the invention reference may be had to the accompanying drawing, in which

Fig. 1 is a horizontal sectional view showing 10 part of one form of the new fence;

Fig. 2 is a front view of part of the fence shown in Fig. 1;

Figs. 3, 4 and 5 are horizontal sectional views 15 similar to Fig. 1 showing the various steps of applying the clip to the post, and

Fig. 6 is a detail view of the fence clip before it is applied to the post.

The new fence comprises a post 10 which, as 20 shown, has a cross section similar to the cross section of a rail and includes a web 11, a vertical flange 12 at one end of the web forming the front face of the post, and a vertical flange 13 at the other end of the web which is somewhat narrower than the flange 12. The post may be made of 25 metal and constitutes one of a series of posts arranged in spaced relation, preferably by driving them into the ground.

On each post is a clip 15 made of heavy steel 30 wire and secured at one end to the post in any suitable manner, as by means of a hook 16 on the clip projecting through an opening 17 in the web. The end portion of the hook lies flat against one side of the web between the flanges so that it is protected by the flanges. From the opening 35 17, the clip extends around one edge of the flange 12 and along the front face thereof where a section 18 of the clip is passed over a strand of fence wire 19 so as to hold the latter against the post. The clip is then bent around the other edge of the flange 12 and extends along the side of the post and around the flange 13. At its end, 40 the clip is provided with a hook 20, the end of which is seated on one side of the flange 13, as shown at 21, and the hook is bent around this flange on the end of the hook as a pivot so that the clip is drawn tightly around the post and the hook lies generally parallel to the web. Any desired number of clips may be applied to the post, depending on the number of fence wires to 45 be secured thereto, and the clips may be arranged in selected positions on the post because the latter is provided with a vertical row of closely spaced openings 17 for securing one end of each clip.

50 The clip is initially in the form shown in Fig. 6,

and in applying it to the post the hook 16 is first inserted through an opening 17 in the web and the clip drawn around the front of the post and over the fence wire 19, as shown in Fig. 3. The free end of the clip is then drawn around the rear flange 13 and hooked over the latter flange, as shown in Fig. 4. The clip and the post are so proportioned that when the end of the clip is hooked on the flange 13, there is a considerable space between the adjacent edge of the flange and the body of the hook, and in this position of the clip the wire 19 is held relatively loosely between the front face of flange 12 and the part 18 of the clip. By reason of this initial looseness, the clip may be applied in the position shown with relatively little effort.

In order to tighten the clip around the post, the hook 20 is hammered toward the front flange 12, as shown in Fig. 5. During the hammering operation, the body of the hook acts as a lever fulcruming on the end of the hook about the inner face 21 of flange 13 so as to draw the clip tightly around the post. When the hook 20 is bent to its final position, shown in Fig. 1, it maintains the clip under high tension and causes the part 18 thereof to press firmly against the wire 19, so that the latter is prevented from rubbing against the clip and the front face of the post.

The new clip is of simple construction and because of the hook 20 and the coacting surface 21 on the rear flange, any looseness of the clip may be easily taken up by simply bending the hook inwardly around the rear flange. In the final position of the hook 20, it lies almost entirely within the space between the flanges 12 and 13, and accordingly the hook is protected by the flanges against breakage.

I claim:

1. A fence comprising a post having a vertical web and vertical flanges at opposite ends of the web extending generally perpendicular thereto, a fence wire lying against the outer face of one flange, and a clip having a hook at one end projecting through an opening in the web, the clip extending from the hook along one side of the web and along said face over the fence wire and then along the opposite side of the web and over the other flange, the clip having another hook at the opposite end engaged with the inner face of the second flange and bent around said last flange toward the first flange on the end of the hook as a pivot.

2. For use in a fence comprising a post having a vertical web and vertical flanges at opposite ends of the web extending generally perpendicular thereto, and a fence wire lying against the outer face of one flange, a clip having a hook on one end insertable through an opening in the web to secure one end of the clip to the post, the clip being adapted to extend from the hook along one side of the post and across said face over the fence wire and then along the other side of

the post and over the other flange, the clip having another hook at the opposite end engageable at its end with the inner face of the second flange and adapted to be bent around said last flange toward the first flange on said end of the hook as a pivot.

3. In a fence comprising a post and a fence wire adjacent the front face of the post, a clip secured at one end to the post for holding the wire on the post, the clip extending from said first end along said front face adjacent the wire and then along one side of the post and over the rear edge thereof and having a hook at its end, the end portion of the hook being bent inwardly toward the post and engaged at its extremity with the post, and the hook being bent out of alignment with the adjacent body of the clip on said extremity as a pivot to tighten the clip on the post.

4. In a fence comprising a post having a vertical web and a flange at one end of the web forming the front face of the post, and a fence wire lying against said face, a clip secured at one end to the post and extending along said face over the fence wire and then along one side of the web and over the rear edge of the post, the opposite end portion of the clip being bent inwardly toward the post in the form of a hook and being engaged at its extremity with one side of the web, and the hook being bent out of alignment with the adjacent body of the clip on said extremity as a pivot to tighten the clip around the post.

5. In a fence comprising a post having a vertical web and vertical flanges at opposite ends of the web extending generally perpendicular thereto, and a fence wire lying against the outer face of one flange, a clip secured at one end to the post and extending along said face over the fence wire and then along one side of the web and over the other flange, the opposite end portion of the clip being bent inwardly toward the post in the form of a hook and being engaged at its extremity with the inner face of the second flange, and the hook being bent around said last flange toward the first flange on said extremity of the hook as a pivot to draw the clip tightly around the post.

6. In a fence comprising a post and a fence wire adjacent the front face of the post, a clip for holding the wire on the post and having one end secured to the post, the clip extending from said first end along said front face adjacent the wire and then along one side of the post and over the rear edge thereof, the clip having a hook at its end, the free end of the hook extending inwardly toward the post and being engaged at its extremity with the post, and the hook being bent toward the front of the post on said extremity as a pivot to tighten the clip on the post.

DONALD C. GARDNER.
